UNITED STATES PATENT OFFICE.

HARRY R. KONIKOFF AND GEDALIA RABINOWITZ, OF NEW YORK, N. Y., ASSIGNEES TO VENUS LAMP CORPORATION, OF NEW YORK, N. Y., A CORPORATION OF NEW YORK.

DESIGN FOR A DISPLAY STAND.

Application filed November 28, 1928. Serial No. 29,054. Term of patent 3½ years.

To all whom it may concern:

Be it known that we, HARRY R. KONIKOFF and GEDALIA RABINOWITZ, citizens of the United States, residing, respectively, in the borough of Manhattan, city, county, and State of New York, and in the borough and county of Queens, city and State of New York, have invented a new, original, and ornamental Design for Display Stands, of which the following is a specification, reference being had to the accompanying drawing, forming part thereof.

The figure is a view in perspective of a display stand, showing our new design.

We claim:

The ornamental design for a display stand, as shown.

HARRY R. KONIKOFF.
GEDALIA RABINOWITZ.
